Primary Examiner — Susan Bennett Hattan*Assistant Examiner* — Rebecca Tsehay(74) *Attorney, Agent, or Firm* — Edward J. Baba; Bozicevic, Field & Fancis LLP(57) **CLAIM**

The ornamental design for slide carrier, as shown and described.

DESCRIPTION

FIG. 1 is a perspective view of a slide carrier; FIG. 2 is a top view of the slide carrier; FIG. 3 is a bottom view of the slide carrier; FIG. 4 is a front view of the slide carrier; FIG. 5 is a back view of the slide carrier; FIG. 6 is a first side view of the slide carrier; and, FIG. 7 is a second side view of the slide carrier. The broken lines in FIGS. 2, 3, and 7 depict parts of the slide carrier that form no part of the claimed design.
